CLOTH PINNING DEVICE

Isidor Kruger, Brookline, Mass.

Application March 24, 1945, Serial No. 584,517

6 Claims. (Cl. 1-49)

This invention relates to fabric pinning machines and pertains more particularly to a pinning or stapling device for temporarily attaching embroidery fabric to a backing sheet of buckram or the like while the design imprinted on the fabric is being embroidered.

The principal purpose of the invention is to provide a pinning machine adapted to form a pinched fold in the limp fabric and its relatively stiff backing sheet, and simultaneously to pass a pin or staple through the fold, thereby fastening the two sheets of material together at selected points around the margin of the embroidery fabric in such a manner that the pin or staple does not damage the material and may readily be removed by hand or by a pincer or other convenient implement.

A further object of the invention is to provide a device which may be employed for pinning or stapling two pieces of flexible material without requiring any special support beneath the lower layer, thereby permitting the machine to be used in fastening materials resting on a relatively soft surface and even on a person's body.

Recommended embodiments of the invention are illustrated in the accompanying drawing, but it will be understood that the structural details of the device herein illustrated and described may be varied to suit particular purposes and conditions without departing from the essence of this invention as set forth in the appended claims.

In the drawing,

Fig. 1 is a plan view of a piece of embroidery fabric fastened to a backing sheet of buckram by the use of the improved machine;

Fig. 2 is a side elevation of the improved pinning machine, with certain parts shown in section;

Fig. 3 is an end view of the machine looking to the right of Fig. 2;

Fig. 4 is an enlarged sectional perspective showing the affixation of the pin or staple to a fold formed in the two layers of material by the machine shown in Figs. 2 and 3;

Fig. 5 is a detail sectional view of a modified form of machine adapted for applying a hairpin type of staple without bending the ends of the pin;

Fig. 6 is a detail view of the pin or staple shown in Fig. 5;

Fig. 7 is a fragmentary plan view of the upper sheet of the materials fastened by the pin of Fig. 6, after removal from the machine; and

Fig. 8 is a detail fragmentary elevation of the anvil portion of the machine shown in Fig. 2.

The machine chosen for the purpose of illustrating in Figs. 2, 3 and 8 comprises a frame 11 having a base portion 12 and an upstanding portion 13; stapling mechanism 14 having a back member 15 suitably mounted, as by soldering, riveting or bolting, to the upright member 13 of the frame; and a hand operated lever 16, pivoted to the frame at 17, for actuating the stapling mechanism. The bed member 15 of said mechanism has an anvil portion 18 at the bottom or outer end thereof, and said anvil portion has one or more downwardly projecting prongs 19 adapted to impinge the surface of the materials to which the base 12 is applied. As illustrated in Fig. 2, the embroidery fabric 19 and backing sheet 20 are laid upon a table or other support 21, and the base 12 of the machine is applied to the fabric as thus supported; but it will be evident, as aforesaid, that the machine may be used without the necessity of furnishing a table or other flat and rigid support. It will also be apparent that the provision of an elongate base member is not essential to the operation of the device, in many cases.

25 The pinning or stapling mechanism 14 comprises an elongate receptacle 22 pivoted at its upper end to the bed member 15 and containing a stack of U-shaped pins or staples 23, a follower 24, and a spring 25 for urging the staples toward 30 the bottom of the receptacle or pin holder, so that they may be forced transversely through an opening 26 in the back of the receptacle by a plunger 27, substantially in the manner exemplified by the common forms of paper stapling machines.

As in such machines, the plunger 27 is carried at the end of a cover 28 hinged at 29 to the receptacle and to the bed member 15, and said cover is normally held in the position shown in Fig. 2 40 by a spring 30, with the plunger 27 adjacent the back of the lowermost staple or pin in the stack 23. The bottom of the pin holder 22 has one or more depending prongs 31, directed toward the anvil 18 and adapted to impinge the fabric layers 45 and form a fold therein, between the anvil and the staples, when the stapling mechanism is closed against the anvil by operating the lever 16. A loop or bail 32 is hinged to the lever 16 at 33 and straddles the stapling mechanism, the loop 50 being removably engaged under a catch 35 on the cover member 28, when the machine is to be used. The loop is disengaged from the catch to permit the cover to be opened when it is desired to refill the pin holder with a new stack 55 of staples.

The mechanical operation of the stapling mechanism is similar to that of the ordinary paper stapling machine. Pressure applied to the back of the cover 28, as by the lever 16 and ball 32 or by the other actuating devices, closes the cover on the pin holder 22 and moves the end of the latter toward the end of the bed or back member 15, thereby causing the plunger 27 to expel the outermost pin of the holder and force its points through the fabric fold 38 and toward the anvil 18.

The anvil of the machine shown in Fig. 2 has a pair of outer slots 36 and a pair of beveled anvil surfaces 37 leading thereto, which tend to spread the points of the staple outwardly under pressure of the stapling mechanism, so that the points lie flat against the back of the fold 38 without reentering the backing, as shown in Fig. 4.

Actuation of the improved pinning machine causes the fabric to be caught by the prongs 19 and 31 and to be pinched into a fold 38, as shown in Fig. 2 (the stapling mechanism being opened in the figure more clearly to illustrate the formation of the fold) so that the double ended pin or staple 39 (Fig. 4) is forced through the four layers of the folded materials and its points are diverged by the inclined walls 37, as aforesaid. The angle of bend of the pin tips 40 is obviously a matter of choice, but it is preferred that the tips be not bent rearwardly into the back of the fold (as is common in paper fastening stapling machines) thereby to avoid injury to the embroidery fabric 19 and to permit more easy removal of the pin when the embroidery of the design 41 (Fig. 1) has been completed.

It will be understood that the buckram backing 20 is dissolved by chemical action in accordance with well known methods to free the embroidery fabric 19, after the embroidery has been completed and the fastenings have been removed.

In the modified form shown in Figs. 5, 6 and 7, the anvil portion 42 of the back member 43 of the stapling mechanism has through openings 44, and the base 45 of the frame 46 has a slot 47, so that a hairpin-like pin 48 may be pushed through the fold 49 of the superposed sheets 50 and 51, without bending the points of the pin. In this arrangement the fold may be pulled out flatwise, as shown in Fig. 7, after the pin has been inserted, and the loop of the pin may be withdrawn slightly so that it lies flat on the fabric. The pin 48 is obviously very easy to remove and it may, if desired, have a loop 52 or other head member, to facilitate the withdrawal by the fingers.

Other variations of the structure of the machine herein illustrated and described may be practiced without departing from the essence of this invention which consists in providing a pinning machine of the paper stapling type with cloth-gripping prongs or projections, formed on the back or anvil portion of the stapling mechanism and on the pin holder, respectively, and depending from the outer ends thereof, thereby to impinge two superposed layers of fabric and pinch a fold therein when the pin holder is closed against the back or anvil by suitable actuating means. As above indicated, the provision of a heavy frame having a base 12, is not essential for many purposes for which the device is suitable; and other devices for actuating the pin holder and its cover may be utilized within the intended scope of this invention.

I claim:

1. In a fabric pinning machine having a back member and a pin holder and cover therefor pivoted to the back member, the cover having a plunger engageable with the outermost pin of a stack within the holder and adapted to expel said pin from the stack toward the back member when the cover and holder are pressed toward said member, fabric-gripping means comprising outwardly directed prongs on the end of said back member and on the end of said cover for impinging a pair of superposed fabric layers to which said ends are applied, and means for pressing the cover and pin holder toward said back member, thereby to pinch a fold of said fabric layers between said ends and force the points of a pin therethrough.

2. In a fabric pinning machine having a back member and a pin holder and cover therefor pivoted to the back member, the cover having a plunger engageable with the outermost pin of a stack within the holder and adapted to expel said pin from the stack toward the back member when the cover and holder are pressed toward said member, fabric-gripping means comprising outwardly directed prongs on the end of said back member and on the end of said cover for impinging a pair of superposed fabric layers to which said ends are applied, and means for pressing the cover and pin holder toward said back member, thereby to pinch a fold of said fabric layers between said ends and force the points of a double-pointed pin therethrough, the back member having an anvil portion disposed opposite the end of the pin holder and having a beveled surface engageable by the pin points and adapted to deflect said points outwardly against the back of the folded material.

3. In a fabric pinning machine having a back member and a pin holder and cover therefor pivoted to the back member, the cover having a plunger engageable with the outermost pin of a stack within the holder and adapted to expel said pin from the stack toward the back member when the cover and holder are pressed toward said member, fabric-gripping means comprising outwardly directed prongs on the end of said back member and on the end of said cover for impinging a pair of superposed fabric layers to which said ends are applied, and means for pressing the cover and pin holder toward said back member, thereby to pinch a fold of said fabric layers between said ends and force the points of a double-pointed pin therethrough, the back member having an anvil portion disposed opposite the end of the pin holder and having openings therethrough to receive the points of the pin.

4. A pinning machine of the character described comprising a frame having a base adapted to be applied to a pair of superposed sheets of flexible material, a stapling device having a back member mounted on said frame, a holder for a stack of U-shaped pins hinged to said back member, and a cover hinged to said holder, said cover having a plunger adapted to expel the bottommost pin of the stack, the back member having an anvil provided with outwardly projecting prongs adapted to impinge the fabric sheets when the base of the frame is applied thereto, and the holder having an outwardly projecting prong adapted to impinge said sheets at a point distant from the anvil, thereby to form a fold in said sheets when the holder is moved toward the anvil, and means associated with said frame and cover for pressing the cover and the pin holder toward the anvil to form said

fold and to force said bottommost pin there-through.

5. A pinning machine of the character described comprising a frame having a base adapted to be applied to a pair of superposed sheets of flexible material, a stapling device having a back member mounted on said frame, a holder for a stack of U-shaped pins hinged to said back member, and a cover hinged to said holder, said cover having a plunger adapted to expel the bottommost pin of the stack, the back member having an anvil provided with outwardly projecting prongs adapted to impinge the fabric sheets when the base of the frame is applied thereto, and the holder having an outwardly projecting prong adapted to impinge said sheets at a point distant from the anvil, thereby to form a fold in said sheets when the holder is moved toward the anvil, and means associated with said frame and cover for pressing the cover and the pin holder toward the anvil to form said fold and to force said bottommost pin through said fold, said anvil having inclined surfaces engageable by the tips of the pin to spread the same outwardly in opposite directions.

6. A pinning machine of the character described comprising a frame having a base adapted to be applied to a pair of superposed sheets of flexible material, a stapling device having a back member mounted on said frame, a holder for a stack of U-shaped pins hinged to said back member and a cover hinged to said holder, said cover having a plunger adapted to expel the bottommost pin of the stack, the back member having an anvil provided with outwardly projecting prongs adapted to impinge the fabric sheets when the base of the frame is applied thereto, and the holder having an outwardly projecting prong adapted to impinge said sheets at a point distant from the anvil, thereby to form a fold in said sheets when the holder is moved toward the anvil, and means associated with said frame and cover for pressing the cover and the pin holder toward the anvil to form said fold and to force said bottommost pin through said fold, said anvil and the base of said frame having openings therein for receiving the prongs of the pin so that the latter remain straight.

ISIDOR KRUGER.
